(57) **CLAIM**

The ornamental design for a vibrator, as shown and described.

DESCRIPTION

FIG. 1 is a front and top perspective view of a first embodiment of a vibrator, showing my new design;
FIG. 2 is a rear and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a front and top perspective view of a second embodiment of the vibrator;
FIG. 10 is a rear and bottom, perspective view thereof;
FIG. 11 is a front view thereof;
FIG. 12 is a rear view thereof;
FIG. 13 is a left side view thereof;
FIG. 14 is a right side view thereof;
FIG. 15 is a top view thereof; and,
FIG. 16 is a bottom view thereof.
The dashed lines in the figures illustrate portions of the vibrator that form no part of the claimed design.

1 Claim, 16 Drawing Sheets
